UNITED STATES PATENT OFFICE.

HUGO CENTERVALL, OF BROOKLYN, NEW YORK.

AERIAL TORPEDO.

1,388,932.

Specification of Letters Patent. Patented Aug. 30, 1921.

Application filed July 27, 1916. Serial No. 111,592.

To all whom it may concern:

Be it known that I, HUGO CENTERVALL, a citizen of Sweden, and a resident of the borough of Brooklyn, county of Kings, city 5 and State of New York, have invented new and useful Improvements in Aerial Torpedoes, of which the following is a specification.

This invention relates to aerial torpedoes 10 of the character designed to be dropped from moving air craft upon hostile ships or fortifications below.

My improved torpedo is designed more 15 particularly for attacks upon vessels at sea, and the object of my invention is to provide a torpedo of this character which will be automatically guided toward the vessel to be struck upon being released from the air craft even though the aviator has not correctly 20 determined the factors of momentum and air resistance which ordinarily determine the trajectory of a projectile.

In the embodiment of my invention which I have selected for illustration I have de- 25 signed the torpedo to be released when vertically above the vessel to be struck and pro- vided it with automatic rudder control for altering the course of the torpedo as it de- scends, to compensate for its deviation from 30 the vertical produced by its momentum, air resistance or from any other cause. In ef- fecting the automatic control of the rudder I make use of the electrical properties of 35 selenium by focusing on a suitable selenium cell or cells an image of the vessel surround- ed by a field of water whereby the resistance of the selenium cell or cells will be altered in proportion to the part of the total field which is occupied by the vessel. Thus, if 40 the position and direction of the projecting range-finder of the torpedo is such that a portion only of the vessel is in the field focused on the cell or cells, the resistance will be different from the resistance when 45 the entire vessel is within the limits of the field. I utilize this variation in electrical resistance to adjust the rudder of the tor- 50pedo so as to alter the course of the torpedo in a direction to bring the entire vessel with- in the field exposed to the cell or cells. In order to accurately guide the torpedo I prefer- 55 ably use a plurality of selenium cells with their circuits balanced one against the other in such manner that the rudder control will be active whenever there is a variance in the

relative resistance of two opposite cells. By this arrangement the guiding means will be given corrective adjustment whenever a de- viation from its course toward the center of the vessel occurs. That is, in order for the 60 rudder to be maintained at normal, equal portions of the fields of each two opposite cells must be occupied by the image of the vessel.

In the accompanying drawings, wherein I 65 have disclosed my improved torpedo,

Figure 1 is a vertical section through the torpedo showing the general arrangement of the parts;

Fig. 2 is a diagrammatic view of the parts 70 of the rudder controlling mechanism showing the electrical connections; and

Figs. 3, 4 and 5 are detail views on en- 75 larged scales of parts of the torpedo shown in Fig. 1.

Referring to the drawings, 1 indicates the shell or container for the explosive 2, the shell being of any preferred configuration and having the usual longitudinal vanes 3 for maintaining it in vertical position dur- 80 ing its downward course. The torpedo will be provided with suitable detonating appa- ratus for firing the charge which may be operated either upon contact with the object struck or in any other suitable manner. 85 This feature of the torpedo forms no part of my invention and is therefore not shown.

The torpedo is provided with a central longitudinal bore or cylindrical chamber 4 extending throughout the length of the tor- 90 pedo and communicating at the upper or rear end with a compartment 5 in which the stem 6 of the guiding rudder 7 projects. The guiding rudder is here shown as a 4- 95 vaned rudder mounted for universal adjust- ment by means of a suitable ball and socket joint. Supported in the end of the bore 4 at the front or lower end of the torpedo is a sighting telescope 8 mounted for universal adjustment relatively to the center line of the torpedo by means of a suitable joint 9 (see Fig. 3). The telescope is provided 100 with suitable optical elements, which I have indicated diagrammatically, to project an image of the surface below the torpedo on to a suitable screen 10 at the rear end of the telescope when the air craft is flying at the altitude usually selected for making at- 105 tacks, about six thousand to ten thousand feet. To adapt the telescope to different 110

elevations the objective lens 11 is vertically adjustable in the telescope tube by means of an adjusting screw 12 extending parallel with the tube along one side thereof.

5 The screen which is shown in Fig. 2, is divided into four quadrants, the area of each of which is occupied by the selenium surface of a suitable resistance cell arranged so that the resistance of each cell will be varied by the intensity of the light projected on that portion of the screen. The four selenium cells which I have marked *a*, *b*, *c* and *d*, respectively, are each connected in a separate circuit containing a cell and a 10 solenoid, the solenoids being indicated in Fig. 2 by letters *a'*, *b'*, *c'* and *d'*, corresponding with the similarly indicated cells. The circuits are all energized from a suitable storage battery 13 carried in the longitudinal 15 chamber of the torpedo.

The four solenoids *a'*, *b'*, *c'* and *d'* are fixedly attached to the wall of the chamber 4 in the space above the telescope with their axes extending radially. The solenoids are 20 arranged in pairs, the solenoids *a'* and *c'* being opposite and the solenoids *b'* and *d'* being above and at right angles to the other ones. Each solenoid is provided with a core 25 operatively connected to an arm 14 forming a longitudinal extension of the telescope. Each pair of opposite solenoid cores are rigidly connected together by an intermediate 30 yoke embracing the arm 14, the arrangement being such that each pair of solenoids will 35 effect a movement of the arm in the direction of their axes without interfering with the movement of the arm at right angles thereto as effected by the other pair of solenoids. The angular position of the telescope 40 in the chamber 4 will be determined by the relative strength of the solenoids as influenced by the selenium resistance in each 45 circuit.

The arm 14 projects beyond the group of 50 solenoids and carries on its end a contact piece 15 wiping against the under face of a circular rheostat 16 which is divided into quadrants as indicated in Fig. 2, the electrical connection being such that each section 55 of the rheostat offers its greatest resistance when the contact shoe is near the center of the under face of the quadrant, the resistance being reduced in proportion to the extent of movement of the contact shoe toward 60 the periphery of the rheostat. As the arm 14 is rigidly attached to the telescope it will be obvious that the position of the contact shoe will be determined by the angular position of the telescope relatively to the axis of 65 the torpedo.

Each quadrant of the rheostat is connected in a separate circuit, each circuit containing a quadrant of the rheostat and a solenoid.

As shown in the diagrammatic view, Fig. 2, 70 the quadrants of the rheostat are indicated

by letters *e*, *f*, *g* and *h* and their respective solenoids by letters *e'*, *f'*, *g'* and *h'*.

The solenoids of this second set are arranged in the compartment 5 adjacent the end of the rudder arm 6, the solenoids being 70 arranged in opposite pairs similar to the arrangement of the solenoids *a*, *b*, *c* and *d*. Each solenoid is provided with a core, the cores of the opposite solenoids being connected by an intermediate yoke 17 as indicated in Fig. 4, the two yokes embracing the stem 6 of the rudder 7 whereby the position of the rudder will be determined by the relative strength of the solenoids as controlled by the respective quadrants of the rheostat 75 80 85 90 95 100 105 110 115 120 125 130

The several rudder controlling solenoids will be energized from a suitable storage battery 18 mounted in the chamber 4 of the torpedo.

In order to vary the focus of the telescope 8 to compensate for the constant approach of the torpedo to the target the screw shaft 12 is adapted to be rotated from a fan or propeller 20 rotatably mounted on the end 90 of the tube forming the central chamber 4, the propeller being connected to the shaft 12 by suitable gearing as shown in Fig. 3.

The operation of a torpedo constructed in accordance with the above described design will now be described. It will be assumed that the electric circuits are provided with suitable switches whereby the circuits may be closed when the torpedo is to be dropped. The switch for the selenium cell circuit should preferably be a pole-changing switch so as to reverse the direction of flow of current through the solenoids and consequently reverse their direction of operation so that if the vessel to be attacked is brighter than the surrounding water field the circuit may be adjusted in one direction, whereas if the vessel is darker than the water field the direction of the circuit will be reversed.

The air craft will preferably be provided with a range-finding telescope supported in double gimbal rings to maintain a vertical position and when the air craft is vertically above the vessel to be attacked the torpedo will be released, the objective 11 of the telescope of the torpedo having been previously adjusted to properly focus the image of its field on the selenium cells. At the moment of release the image of the vessel to be attacked will lie substantially at the center of the screen 10 containing the four selenium cells, equal parts of the image of the vessel occupying the adjacent portions of the opposite cell. The lateral movement of the torpedo, due to its momentum acquired when traveling with the air craft, will cause the image of the vessel to move across the screen toward one side thereof thereby causing more of the area of at least one cell to be occupied by the image of the vessel than its opposite cell. The cell or cells upon which 105 110 115 120 125 130

the greater portion of the image of the vessel is projected will have their resistance either increased or decreased, depending on whether the vessel is darker or lighter than its field, and the opposite cell or cells will have their resistance inversely altered to thereby correspondingly vary the strength of the opposite solenoids of each pair *a, c* and *b, d*. The change in the strength of solenoids will obviously produce an angular adjustment of the telescope 8 from its balanced central position, thereby causing the contact shoe 15 and the arm 14 of the telescope to be shifted out of the center of the rheostat 16 in a direction to cut out the resistance in one or perhaps two of the quadrants of the rheostat, thereby upsetting the balance of the rudder-controlling solenoids and causing the rudder to be tilted in a direction and to an extent corresponding with the movement of the telescope.

It will be understood that the pole-changing switch is so adjusted as to cause the angular movement of the telescope produced by the variations in resistance of the selenium cells to cause the telescope to follow the vessel, that is, the movement of the telescope tends to bring the image of the vessel to the center of the screen 10. The return of the image toward the center of the screen tends to equalize the resistance of the circuits through the selenium cells, but such equalizing of the circuits has the effect of tending to return the telescope to its central position, which movement, unless the change of direction of the torpedo as effected by the rudder has brought the torpedo back to its vertical position over the vessel, will again disturb the balance of the telescope-controlling solenoids and produce an angular movement of the telescope. The result is that the telescope will maintain an average inclination to the vertical axis of the torpedo depending upon the extent to which the torpedo has been carried away from the vertical line at the point of its release, the inclination of the telescope maintaining the rudder in an inclined position to deflect the torpedo in its downward path until its return to a position vertically over the vessel to be attacked. In such position the telescope and rudder will be aligned with the axis of the torpedo and will guide the torpedo in a straight course to its target.

If the target be moving the telescope will obviously follow its movement and continue to deflect the torpedo from its true downward path and cause it to strike the vessel.

I have not attempted to show the structural details of various electrical elements making up my improved torpedo control, as such details may obviously be varied within wide limits. For instance, the pole-changer switch illustrated in Fig. 2 may be of any design capable of simultaneously re-

versing all four circuits and also affording a cut-out position. As shown, the switch comprises a rotating disk of fiber with four angular contacts on its under face adapted upon rotary adjustment of the disk to bridge the gap between the fixed segmental contacts through which the wires of the circuits are joined.

Instead of connecting the circuits through the selenium cells directly to the solenoids controlling the telescope, I may utilize local circuits for the several solenoids and control such circuits through sensitive relays operated through the selenium cells.

I claim:

1. In an aerial torpedo the combination of a guiding device, an image-forming directing device adapted to be trained on the object to be attacked, and means controlled by said directing device for operating said guiding device to cause said guiding device to guide said torpedo back to the line of movement toward said object when deflected therefrom.

2. In an aerial torpedo the combination of a guiding device, a movably mounted image-forming directing device adapted to be trained on the object to be attacked, and means controlled by said directing device for operating said guiding device to cause said guiding device to guide said torpedo back to the line of movement toward said object when deflected therefrom, said directing device comprising means for adjusting the device relatively to the torpedo to maintain the sighting device trained on the object.

3. In an aerial torpedo the combination of a torpedo body, a guiding device therefor, an image-forming directing device comprising a screen sensitive to the projected image of the object to be attacked, and means controlled by the position of said image on the said screen for operating said guiding device to maintain the torpedo on its predetermined course.

4. In an aerial torpedo, the combination of a torpedo body, a guiding device therefor, an image-forming directing device comprising a screen sensitive to the projected image of the object to be attacked, means controlled by the position of said image on the said screen for operating said guiding device to maintain the torpedo on its predetermined course, and means for adjusting the directing device during the approach of the torpedo to the object to maintain the image of the object focused on the screen.

5. In an aerial torpedo, the combination of a torpedo body, a guiding device therefor, an image-forming directing device having at the image-forming position a light sensitive electrical resistance element, and means for operating said guiding device controlled by the resistance of said element as varied by the movement of the image of the object to

80

90

95

100

110

115

120

125

130

be attacked to return said torpedo to the line of movement toward said object upon any departure therefrom.

6. In an aerial torpedo, the combination of
5 a torpedo body, a guiding device therefor,
an image-forming directing device having at
the image-forming position a light sensitive
electrical resistance element, means for op-
erating said guiding device controlled by the
10 resistance of said element as varied by the
movement of the image of the object to be

attacked to return said torpedo to the line of movement toward said object upon any departure therefrom, and means controlled by said varying resistance to adjust said di-
recting device to maintain it pointed at the
said object, and thereby maintain the image
of the object on the adjusting element. 15

Signed at New York city, in the county of
New York and State of New York, this 22nd 20
day of July, 1916.

HUGO CENTERVALL.
